UNITED STATES PATENT OFFICE.

JOHN ORVAL EDMOND, OF CYPRESS, INDIANA.

HEATER FOR AUTOMOBILES.

1,290,139.

Specification of Letters Patent. Patented Jan. 7, 1919.

Application filed January 12, 1917. Serial No. 142,003.

To all whom it may concern:

Be it known that I, JOHN O. EDMOND, a citizen of the United States, residing at Cypress, in the county of Vanderburg, State 5 of Indiana, have invented a new and useful Heater for Automobiles; and I do hereby declare the following to be a full, clear, and exact description of the invention, such as will enable others skilled in the art to which 10 it appertains to make and use the same.

This invention relates to an improved heater for automobiles, and one of the objects of the invention is to provide a heater of this kind designed to use the exhaust 15 products of combustion from the exhaust manifold for heating purposes.

A further object of the invention is to provide a casing having upper and lower chambers in communication, through which 20 the exhaust passes, in order to radiate required heat; said casing to be suspended immediately below the floor of the automobile to keep the occupant warm.

A further object of the invention is to provide a casing having means, whereby the 25 casing may fit automobiles of different widths.

A further object of the invention is to provide a heater casing, the lower chamber 30 of which is divided into a multiple of compartments, in combination with means to be manually operated whereby said compartments may be thrown in communication with each other.

35 In practical fields, the details of construction may necessitate alterations, falling within the scope of what is claimed.

The invention comprises further features and combination of parts, as hereinafter set 40 forth, shown in the drawings and claimed.

In the drawings:

Figure 1 is a plan view of an automobile, showing the two heaters applied.

Fig. 2 is a view partly in elevation and 45 partly in section, showing the two heaters suspended from and below the floor of the automobile and in connection with the exhaust manifold.

Fig. 3 is a sectional view on line 3—3 of 50 Fig. 2, showing parts below in plan.

Fig. 4 is an enlarged detail view in elevation of one of the heaters, showing parts in section, and showing the guides for the heater.

Fig. 5 is a sectional view on line 5—5 of Fig. 4.

Fig. 6 is a sectional view on line 6—6 of Fig. 4.

Fig. 7 is a cross sectional view on line 7—7 of Fig. 4.

Fig. 8 is a view of another form of heater.

Referring more especially to the drawings, 1 designates a conventional form of automobile, and 2 designates the side rails of the body of the automobile. The bottom of the automobile forward of both seats thereof is provided with openings 3 disposed transversely, and 4 denotes a casing of each heater. The casing of each heater comprises the upper and lower parts 5 and 6 which are elongated and hollow, and are constructed of any suitable metal preferably sheet metal. The upper and lower parts of the casing of each heater are rectangular in cross section, as shown clearly in Figs. 2 and 7. Said upper and lower parts have their adjacent portions provided with flanges 7, which are secured together by the rivets 8, in order to secure the two parts of the casing together. The upper portion of the upper part 5 of the casing is provided with a laterally extending marginal flange 9 L-shaped in cross section and extending 75 downwardly, and which flanges 9 are upon opposite longitudinal sides of the part 5. These flanges 9 engage guide flanges 10 of the end supporting plate 11, which extend transversely of the end parts of the opening 3 of the bottom of the automobile, and rest upon the flanges 12 of the side rails 2 of the automobile body. The inner portions 80 of the opposite side of said plates 11 have lugs 13, which are embedded in the floor of the automobile body, as shown clearly in Figs. 1 and 2, there being bolts extending 85 upwardly through the floor of the automobile, and through said lugs 13. These bolts 14 have nuts 16 on their lower ends, and their upper portions have right angle ex- 100

tending parts 17 to overlie the side portions of the plates 11, and terminate in downwardly extending portions 18, to extend through the plates 11, and the flanges 9, 5 thereby supporting the casing of the heater. By the provision of the said plates 11 and their guides and the side flanges of the casing of said heater, the heater can be made to fit automobile bodies of different widths. 10 The lower part 6 of the casing of each heater has a chamber, which is divided into a multiple of compartments 19, by means of the partitions 20. However, these partitions 20 do not extend the entire width of the 15 chamber of the lower part 6 of the casing; hence passages 21 are provided. Hinged at 22 to said partitions 20 are closures 23, which have eyes 24. Connecting said closures by means of the eyes, are the wire rods 25, and 20 one of these wire rods at the end of the heater is flexible and is extended through the end wall of the casing 6, and over the pulley 26, and then over the pulley 27 in the arm 28 and is connected at 29 to the arm 30 25 of the rocking disk 31. One of said closures at one end of the casing has a spring 32 connected to it, and which in turn is connected at 33 to the wall of one of the end compartments. By applying the operator's foot on 30 the toothed edge 34 of the rocking disk 31 (which is pivoted upon the pin 35) and moving the disk 31 in the direction of the arrow *a*, the spring 32 will open the closures 23 simultaneously, which will throw all the 35 compartments 19 in communication with each other simultaneously. The upper part 5 of the casing of each heater is provided with a single elongated chamber, the bottom of which at both ends is provided with 40 openings 35 and 36 in communication with the end compartments of the lower part 6 of the casing of each heater. Heat radiating tubes 37 arch upwardly from the top of the part 5 of the casing of each heater, and 45 mounted over these tubes and secured to the part 5 of said casing is a hood 38, thereby forming a heat chamber 39, in which the heat radiating from the tubes 37 is confined, whereby the feet of the occupant of the 50 automobile may be kept warm.

A conventional form of exhaust manifold pipe 40 is illustrated, which is provided with the usual muffler 41. A suitable collar 42 (which is split and has the ears 43) is 55 clamped upon the exhaust manifold pipe by means of the screws 44, which pass through the ears 43. This collar 42 has an extension 45 provided with a threaded opening 46 which is in registration with the opening 47 60 of the manifold pipe 40. Threaded into the openings 46 and 47 is a suitable nipple 48, which is also in turn threaded into the extension 49 of the valve casing 50, thereby connecting the valve casing and exhaust 65 manifold in communication. The valve cas-

ing is provided with additional extensions 51, 52 and 53. Threaded into the extensions 51 and 52 are pipes 54 and 55, which in turn are connected to the elbows 56. Short pipes 57 are connected to the elbows 56. One end 70 of the casing of each heater has the flanged end 58 of the pipe section 59 secured to it, as at 60, whereby the pipe section 59 is in communication with one of the end compartments of the lower part of said casing. 75 The short pipe sections 57 have telescopic slip connections with the pipe sections 59, in order to accommodate the vibrations of the body of the automobile. These slip joints are also afforded, in order to permit 80 the heating system to be applied to various automobiles, where the distance or space between the body of the automobile and the exhaust manifold vary. All the pipe sections and the valve-casing may be constructed 85 of any suitable metal. The end 61 of the casing of each heater has a pipe section 62 secured thereto by the rivets 63 passing through the flange 64. This pipe section 62 is in communication with one of the end 90 compartments of the lower part of said casing. A valve pin 65 is mounted in suitable bearings of the valve casing 50 and secured to said pin by means of a feather 66 is the valve 67, which normally closes the 95 passage through the nipple 48. Carried by one end of the valve pin is an arm 68, to which a coil spring 69 is connected. The spring is in turn connected to a lateral pin 70 of the clamping collar 71. This collar 71 100 is a part of the upper portion 72 of the clamping band 73, which surrounds the muffler 41. The upper portions 72 of said band 73 are secured together by the nut and bolt as shown at 74. Mounted upon the 105 floor of the automobile, forward of the front seat is a segment rack 75, and pivoted at 76 in a bearing of the floor of the automobile is a lever 77 having a foot piece 78 and the arm 79. A suitable cable, wire or the like 80 110 has one end connected to the arm 79 of said lever 77 and its other end 81 to the lever 65 of the valve pin. A spring tensioned foot dog 82 is carried by the lever 77, to operate with the teeth of the segment rack, 115 to hold the lever in different adjusted positions. When the foot of the operator is applied to the foot piece 78, the dog 82 is depressed from engagement with said teeth of the segment, whereby the lever may be 120 adjusted as desired. When the lever is moved in the direction of the arrow *b*, the cable 80 is pulled, thereby rocking the arm 68 of the valve pin, so as to rock the valve 67, whereby the passage through both pipe 125 sections 54 and 55 and the heaters, and the passages through the exhaust manifold and said nipple 48 are simultaneously in communication, whereby the exhaust products of combustion from the manifold may pass 130

through the pipe sections 59 into the corresponding ends of the casings of both heaters. The exhaust or products of combustion will then pass through the opening 5 into the elongated chamber of the upper part of said casing, a portion of which said exhaust following an undulated course to the heat radiating arched tubes 37, thereby heating the chamber 39. However, when 10 it is desired to prolong the passage of the exhaust through each heater, and at the same time partially muffle the same and to intensify the heat in the elongated chamber of the upper part of the casing, the closures 15 23 are thrown open simultaneously, by manipulating the disks 31. The exhaust after passing through the heater passes to the atmosphere through the pipe 62.

In Fig. 8 the heater is the same and complies with the foregoing description, with the exception that the tubes 37 and the hood 38 are eliminated. Another heater may be applied or connected to the extension 53, if it is so required.

25 The invention having been set forth what is claimed as new and useful is:—

1. In an automobile heater, a casing having a heat chamber and provided with partitions subdividing said chamber into a multiple of compartments, said partitions having passages at the ends thereof, closures for said passages, spring means to hold said closures normally open, connections between said closures, and means manually operated 35 to simultaneously close said closures.

2. In an automobile heater, a casing having a chamber and provided with inlet and exhaust ports for the exhaust from an exhaust manifold, said chamber having partitions subdividing the same into a multiple 40 of compartments, means of communication between said compartments, spring tensioned closures for said means of communication, and means for simultaneously closing 45 the closures.

3. In an automobile heater, a casing provided with a multiple of compartments and having inlet and outlet ports for the exhaust from the exhaust manifold, said compartments having passages of communication, and means to operate with said passages to control the exhaust from one compartment 50 to another simultaneously.

4. In a heater, a casing having upper and 55 lower chambers having passages of communication therebetween at both ends, the lower chamber having inlet and exhaust ports for the exhaust from an exhaust manifold, said lower chamber having a multiple 60 of compartments provided with passages of communication, means to control the flow of the exhaust through said compartments.

5. In a heater, a casing having upper and 65 lower chambers having passages of communication therebetween at both ends, the

lower chamber having inlet and exhaust ports for the exhaust from an exhaust manifold, said lower chamber having a multiple of compartments provided with passages of communication, means to control the flow 70 of the exhaust through said compartments, a casing hood rising from the casing of the upper chamber and having a chamber, and a multiple of looped radiating tubes rising from the upper wall of the lower chamber 75 through said upper chamber and extending into the chamber of the hood.

6. In a heater for an automobile, the combination with the floor of the automobile having a transverse opening, of a heating 80 unit having a casing mounted in said opening, of transverse plates, one at each end of said opening supported upon the side rails of the body of the automobile, said plates and the sides of the casing having interengaging flange connections to support the casing.

7. In a heater, a casing, means having flange connections with the casing and adapted to rest on the side rails of the body 90 of an automobile for supporting said casing, said casing having upper and lower chambers provided with openings of communication therebetween at both ends, the lower chamber having inlet and exhaust 95 ports for the exhaust from an exhaust manifold and provided with a plurality of partitions dividing the lower chamber into a plurality of compartments, said partitions having passages at the ends thereof whereby the compartments are in communication, hinged members carried by the partitions for closing and opening said passages of communication, means connecting said hinged members, whereby when one of said 100 members is actuated all of said members will close simultaneously, spring means connecting one of said members and one of the end walls of the lower chamber, thereby holding all of said members open, means 105 connected to one of said hinged members, whereby all of them may be closed simultaneously against the action of the spring means.

8. In a heater, a casing, means to support 115 the casing suspended from the floor of the body of an automobile, said casing having upper and lower chambers provided with openings of communication therebetween at both ends, a plurality of heat radiating 120 tubes rising upwardly from the upper wall of the lower chamber through the upper chamber and its upper wall and being arranged in pairs, connections of communication between the upper ends of the tubes of 125 each pair, a hood over said radiating tubes, said lower chamber having a plurality of compartments, passages for communication therebetween, means for opening and closing 130 said passages simultaneously for con-

trolling the flow of heated gases through said compartments, spring means for opening said closing means, and manually operated means for actuating said closure means.

5 9. In an automobile heater, a casing provided with a multiple of compartments having inlet and outlet ports for the exhaust from the exhaust manifold, passages of communication between said compartments, and
10 means for opening and closing said passages

simultaneously for controlling the flow of heated gases through said compartments.

In testimony whereof I have signed my name to this specification in the presence of two subscribing witnesses.

JOHN ORVAL EDMOND.
